VACUUM CLEANER NOZZLE

Erik Edström, Stockholm, Sweden, assignor to
Electrolux Corporation, Dover, Del., a corpora-
tion of Delaware

Application May 11, 1934, Serial No. 725,033
In Germany May 13, 1933

1 Claim. (Cl. 15—158)

This invention relates to nozzles for vacuum cleaners which are useable with or without bristles. The advantage of such a nozzle is that it can be advantageously used on carpets or on floors. It is previously known to have separate brush attachments for vacuum cleaner nozzles. The disadvantage of such an arrangement is that the user must remove the brush attachment in order to use the nozzle for rugs or the like. Furthermore, the attachment is likely to be lost.

The present invention provides a brush attachment which is incorporated in the nozzles and is preferably of such construction that the bristles are movable above or below the mouth of the nozzle body. In some forms of my invention I provide independent movement of brushes on either side of the nozzle mouth which is advantageous in some forms of cleaning since some of the bristles may be positioned below the mouth of the nozzle body and others above and out of cleaning position.

The invention will be explained by reference to the accompanying drawings, forming a part of this specification, and of which:

25 Fig. 1 is a front elevational view of a vacuum cleaner nozzle embodying the invention;

Fig. 2 is a plan view of one end of the nozzle;

Fig. 3 is a plan view of the other end of the nozzle;

30 Fig. 4 is an end view of the nozzle;

Fig. 5 is a vertical sectional view taken on the line V—V of Fig. 1;

Fig. 6 is a horizontal cross-sectional view of one end of a part of the nozzle;

35 Fig. 7 is a vertical cross-sectional view of one end of the nozzle;

Fig. 8 is a sectional view taken on the line VIII—VIII of Fig. 7;

Fig. 9 is a sectional view on an enlarged scale;

40 Fig. 10 is a sectional view of one end of the nozzle;

Fig. 11 shows a modified form of construction embodying the invention;

Fig. 12 is a front elevational view of still an-
45 other embodiment of the invention;

Fig. 13 is a plan view partly in cross-section of the structure shown in Fig. 12;

Fig. 14 is a vertical sectional view taken on the line XIV—XIV of Fig. 12;

50 Fig. 15 is a horizontal view on an enlarged scale of the structure shown in Figs. 12 and 13; and

Fig. 16 is a detail view.

Referring more particularly to the structure shown in Figs. 1 to 10, the nozzle comprises a
55 nozzle body 10 having a tubular portion 11 adapt-

ed to be connected to the suction conduit of a vacuum cleaner. The nozzle body 10 has an elongated mouth at the lower part thereof. At the left-hand of the nozzle body are ears 12 which are preferably cast integral with the nozzle body. The nozzle body may be made of aluminum or a like rigid material. At the opposite end (the right as shown in Fig. 1) are ears 13. These ears have bores and constitutes bearings for rods 16 and 17 extending to either side and longitudinally of the mouth of the nozzle. Each of the rods 16 and 17 carries a row of bristles 14 and 15 respectively. The ends of rods 16 and 17 are formed by bushings 18 and 19 which are rotatably journaled in the ears 12 and 13, respectively. In order to prevent axial movement of the brush carriers in the bearings, rings 20 are provided which set onto the bushings 18 and 19 and bear against the side surfaces of the ears 12 and 13. Cup-shaped members 21 fit within members 18. These members extend around the outside end surfaces of member 12 and over the outside edge thereof and are rifled at 22 to form handgrips. Each of the members 21 is provided with a bottom part 23 against which a pressure 25 spring 24 bears. The other ends of these springs press against cross-pins 25 fastened in bushings 18. In order to permit axial movement of the members 21 they are provided with slits 26 corresponding to the pins 25. The outer ends of the 30 ears 12 are provided with bosses or projections 27 which are adapted to enter corresponding apertures or holes 28 in members 21. The outer openings of the ears 13 are covered by disks 29 in order to prevent entry of dust into the bear- 35 ings.

As shown in Figs. 1 and 4 the bristles 14 and 15 project below the nozzle body and the nozzle is in effect a brush nozzle. In order to convert the nozzle into a rug nozzle it is merely necessary 40 only to pull the members 22 outwardly, turn the brush carriers 180° and let go of the members 22. On pulling members 22 outwardly the projections 27 leave apertures 28 whereby the members 22 can be turned and the pull is opposed by 45 the stress of the spring 24. Turning of members 22 causes turning of pins 25 and consequently of members 18, 16, 17, and 19. When the bristle carriers have been turned through 180° the projections 27 which are diametrically opposed will 50 slip into the opposite openings and therefore the bristles will be locked in vertical or non-cleaning position. The forward brush members may be left up as shown in Fig. 5 with the rear brush member down so that the nozzle mouth 45 is 55

above the floor and the rear brush carries along dust or litter to be sucked into the nozzle.

A somewhat different form of construction is shown in Fig. 11. Ears 12 and 13, like the previous embodiment, are fixed with respect to the nozzle body. Members 18 and 19 are turnably mounted in ears 12 and 13 and are longitudinally movable therein. The brush rods 16 and 17 are attached to members 18 and 19 as by screws. The screw 30 at the left-hand of the nozzle projects outwardly and is adapted to enter a recess 31 in ear 12. A second recess 31a is formed in ear 12 diametrically opposite recess 31. The outer end of ear 12 is formed with a shoulder 32 against which a spring 33 seats. This spring is turned inwardly into member 18 so as to be under tension and is fastened under a head bolt 34 which screws into a transverse part 35 of member 18. Member 19 passes around the outside of ear 13 and is rifled at 36 to provide a handgrip.

In order to turn the bristles in this embodiment into or out of cleaning position member 19 is pulled against the action of spring 34 whereby screw 30 is disengaged from the recess 31 and can be turned 180° so as to enter and lock in recess 31a.

The arrangement shown in Figs. 12 to 16 differs from the above described forms more particularly in that the bristles 14 and 15 are moved simultaneously. Rods 37 pass through bearing members 18 and 19 and the brush carriers 16 and 17. The rods 37 are rigidly connected to oval-shaped caps 38 and 39 by means of nuts 40 and 41. Rods 37 are provided with helical grooves 42 which extend a one-half turn with respect to the circum-

ference thereof. The grooves are cut in opposite sense with a left-hand on the one and right-hand on the other. These helical grooves cooperate with projections 44 (Fig. 16) which are screwed firmly into the bearing members 18 and 19. Both rods 37 are longer than the distance between the rod ends of the members 18 and 19 by the distance a . This distance is equivalent to the circumferential extent of the helical grooves. 5

By moving the cross pieces 38 and 39 to the right (in the figures) and thereby the rods 37 by the length a , the members 18 and 19 and consequently the brush carriers and the brushes 14 and 15 will be turned 180°. The brushes are locked in their extreme positions by straightening out the ends of the helical grooves longitudinally of the rods 37. Movement in the opposite direction returns the brushes to their original position. 10 15

It will be obvious to those skilled in the art that various alterations in the structure may be made within the scope of the invention. 20

What I claim is:

A nozzle for vacuum cleaners including a nozzle body having an elongated mouth, a hollow tube 25 turnably mounted on each side of said mouth, brush bristles secured to said tubes, rods formed with helical grooves passing through said tubes, projecting members on said tubes engaging said grooves, and means for simultaneously moving said rods axially, whereby said tubes are caused to turn and carry said brush bristles into and out of cleaning position. 30
